Des. 932

S. H. Ransom, of Albany, N. Y.
Letter Patent No. 932. Dated Aug. 25. 1857.

The schedule referred to in these letters Patent, and making part of the same.

Be it known that I, Samuel H. Ransom, of the city of Albany, and State of New York, have produced a new and original ornamental design for the plates of a stove, called by me the Ocean Stove, and I declare the annexed delineations forming part of this specification, are accurate representations of the said plates which are combined to form the said stove, with their ornamental parts; the left front door, and the right side plate with doors, not represented being symmetrically similar to the right front door, and the left side plate with door, as represented.

What I claim as my production, and desire to secure by Letters Patent, is the combination and arrangement of ornamental figures and forms, represented in the accompanying delineations forming together the ornamental design for the plates of a stove.
